UNITED STATES PATENT OFFICE

ALBERT A. GECK, OF FRANKLIN, PENNSYLVANIA, ASSIGNOR TO COLBURN MACHINE
TOOL COMPANY, OF FRANKLIN, PENNSYLVANIA, A CORPORATION OF PENNSYLVANIA.

DRILL-PRESS.

1,115,659.

Specification of Letters Patent.

Patented Nov. 3, 1914.

Application filed October 25, 1913. Serial No. 797,278.

To all whom it may concern:

Be it known that I, ALBERT A. GECK, citizen of the United States, residing at Franklin, in the county of Venango and State of 5 Pennsylvania, have invented certain new and useful Improvements in Drill-Presses, of which the following is a specification.

This invention relates to improvements in 10 drill presses, and more especially to improvements in feed-shaft-supports for the drill press shown and certain features, whereof, and to which this invention is related, are fully described in Letters Patent of the United States issued to Leslie H. Colburn on the 13th day of February 1912, No. 15 1,017,635, and on the 22nd day of July 1913, No. 1,068,324, both of which Letters Patent and the inventions covered thereby have been duly issued to the Colburn Machine 20 Tool Company, of Franklin, Pa.

The construction, object, and utility of 25 this invention are herein set forth with sufficient clearness to enable those skilled in the art of machine-tool construction, to make and use the same.

The construction whereby my invention is embodied, is fully illustrated in the drawings, the various figures of which are as follows:

30 Figure 1 is a side elevation of a portion of a drill press, showing my improved feed-shaft-support applied thereto. Fig. 2 is a side elevation of the feed mechanism with the shaft-support removed for the purpose 35 of more clearly illustrating the construction of said mechanism, that the application and utility of said support may be more clearly pointed out. Fig. 3 is a front elevation of 40 said feed mechanism showing the application of said support thereto.

It will be noted, from an inspection of 45 said drawings, that the feed mechanism here shown, is that whereby the spindle 1 of the drill press is actuated for the purpose of feeding the drill to its work, when said drill is in operation. This feed mechanism consists of a revoluble shaft 2, upon which, a pinion 3 is rigidly secured and arranged to mesh with the rack 4, upon the spindle-sleeve 5. The inner end of said shaft is provided with a bearing within the column 12 of the press. Upon the outer end of said shaft 2 is mounted a worm-wheel 6 which is arranged to revolve said shaft 2. For the 55 purpose of driving said worm-wheel a worm

7 is provided, which engages said wheel, and is mounted upon a shaft 7^s, which is provided with bearings 7^b upon the pivoted bracket 8, which has its pivotal point about the shaft 9, that passes through the rear end 60 of said bracket, and by means of which said worm-shaft 7^s is driven through the gears 7^c. The forward end of said bracket 8 is adapted to move vertically in such a manner that said worm may be engaged with 65 and disengaged from the wheel 6 which it actuates. For the purpose of accomplishing said vertical movement of said bracket, I provide a cam-lever 10 and mount the same upon a pin 11, one end of which is inserted in the frame or column 12 of said press. The construction of this feed mechanism is such that both the shaft 2 and the pin 11 necessarily project for a considerable 70 distance outward from their bearings in said column 12 and when heavy work is being done by the drill, there is a stress between said worm and gear that tends to spring them out of mesh and thus to spring shaft 2 and pin 11 apart, and to counteract this 75 tendency and prevent such springing apart of said shaft and pin I connect the projecting ends thereof by means of a supporting yoke which comprises, at its upper end, a capped bearing 13 for the reception and 80 engagement of said shaft 2, and at the lower end thereof, a solid bearing 14 for the reception and engagement of the outer end of the pin 11 which projects beyond said cam 10. Inasmuch as it is necessary to position 85 said support outside of the index plate 15, (which is fully described in said Letters Patent No. 1,017,635) which is graduated and provided with means to gage and indicate the depth of holes to be drilled, it is 90 desirable that the yoke construction be such as not to materially obstruct the operator's view of said plate 15, and for this reason said bearings 13 and 14 are connected together by means of arms 16, which are positioned a considerable distance apart, so that the indicator 17 and the graduations upon said plate 15, when in proximity to said indicator, are plainly in view. Through the application of said yoke, shaft 2 and pin 11 95 are mutually supported and held in the proper relation to each other, so that any tendency on part of said worm gear to spring them apart, and thus permit an improper meshing of said worm and gear 100 105 110

wheel, which would result in inefficient service, is prevented and the object of this invention is fully attained.

I claim:

5. The combination with the column of a drill press, of a vertically-movable spindle, a sleeve for said spindle, a rack secured to said sleeve, a pinion meshing with said rack for the purpose of actuating said spindle longitudinally, a shaft for said pinion having a bearing for its inner end within said column, a worm-wheel affixed to the outer end of said shaft, a worm positioned below said wheel, and arranged to be operatively engageable
10. therewith and disengageable therefrom, a pivotal bracket provided with bearings for
- 15.

said worm, means for revolving said worm, a cam positioned below said worm and adapted to actuate said bracket to cause the engagement of said worm with said wheel, 20 a pin upon which said cam is mounted provided with a bearing for its inner end within said column and means rigidly connecting the outer end of said worm-wheel shaft and the outer end of said pin, for the purpose 25 set forth.

In testimony whereof I affix my signature in presence of two witnesses.

ALBERT A. GECK.
